TOBACCO MANIPULATING MACHINE

Félix Frédéric Ruau, Deptford, London, England,
assignor to Molins Machine Company, Limited,
Deptford, London, England

Application February 17, 1938, Serial No. 191,065
In Great Britain April 16, 1937

2 Claims. (Cl. 131—66)

This invention is for improvements in or relating to tobacco manipulating machines in which a continuous tobacco rod or filler is formed, such for example as continuous rod cigarette making or tobacco packaging machines in which a stream of 5 uncompressed or substantially uncompressed tobacco is given the whole or substantially the whole of its compression whilst in a converging passage, which passage is provided for shaping the filler rod and for gradually converging the paper web to a U cross-section.

In such machines it is usual to pass the stream of uncompressed tobacco through a passage having converging side and top walls. The fact 15 that the side walls are converging is not disadvantageous to any noticeable extent, because the tobacco stream is moved through the passage on the web of cigarette paper, the longitudinal side portions of which are folded upwardly in the passage and embrace that part of the tobacco stream which would otherwise be engaged by the side converging walls, and the side walls do not, therefore, tend to arrest the forward movement of the tobacco stream. The top wall of this converging passage, however, is also a converging wall and has, prior to this invention, consisted of a stationary surface which engages with the upper surface of the tobacco stream, thereby, as will be appreciated, tending to arrest the movement 25 of the tobacco. From experiments it has been presumed that the action of this top wall or tongue, as it is usually called, tends to disarrange the tobacco stream and increases any irregularities thereof. It is an object of the present invention to reduce this disarrangement of the tobacco filler by avoiding the use of the stationary tongue as aforesaid.

According to the present invention there is provided a cigarette making machine comprising 40 means to feed a stream of tobacco and a web of wrapping material to folding elements for wrapping the web around the tobacco, a converging passage to fold the web to a U formation with the tobacco stream positioned in the base of the U, guard means to keep the tobacco away from the longitudinal edges of the web in the converging passage, a movable surface or surfaces in said converging passage and wedge shaped guide surfaces disposed between said guard means 45 and the movable surface or surfaces to co-operate with said movable surface or surfaces to give the tobacco stream the whole or substantially the whole of its compression independently of the action of the converging passage in folding the web into U formation.

It will be seen that by this construction the tobacco is given its compression in the converging passage and only a relatively small area of stationary surface (i. e., the wedge shaped guides) is in contact with the tobacco during such compression.

The movable surface may comprise a wheel rotatable about an axis transverse to the direction of movement of the web through the converging passage, and if desired the wedge shaped 10 guide surfaces may extend from the guards (for example, the guide surfaces may be integral with the guards) to the movable surface. The moving surface is preferably located at a position as near as possible to the narrow end of the converging 15 passage in order to ensure that the minimum expansion of the filler will occur after the filler has been formed by the compression of the tobacco stream by the moving surface co-operating with said wedge shaped guide surfaces.

A passage having substantially parallel walls 20 may lead from the narrow end of the converging passage to the folding elements and be provided with guards for the longitudinal edges of the web, and means may be provided in the substantially parallel passage further to compress or to hold down the tobacco in the parallel passage and to guide the tobacco filler to the folding elements. The means to further compress or to hold down the tobacco filler in the substantially 25 parallel passage may comprise a stationary surface or a moving surface, for example, a roller. The means to feed the filler and the web to the folding elements may comprise an endless band and the band and the web may be folded from a 30 flat condition to U form substantially together.

One embodiment of the invention will be described by way of example with reference to the accompanying drawings in which—

Figure 1 is a side elevation of a part of a non-compression cigarette making machine.

Figure 2 is a plan of a part of Figure 1.

Figure 3 is a view in the direction of the arrow 3. Figure 2, some parts being omitted.

Figures 4 to 8 inclusive are sections, drawn to an enlarged scale, on lines 4—4, 5—5, 6—6, 7—7, 45 8—8 respectively of Figure 2.

Figure 9 is a section, drawn to an enlarged scale, on the line 9—9 of Figure 2.

Like reference numerals refer to like parts 50 throughout the specification and drawings.

Tobacco is supplied to the mechanism by tobacco feeding mechanism 10 of any well known construction and the tobacco is showered on to the surface of an endless band 11 which moves 55

in the bottom of a trough 12 positioned beneath a chute (not shown) through which the showered tobacco falls. The shower of tobacco extends lengthwise of the endless band 11. The band 11 as it moves beneath the chute gradually collects tobacco on its surface until when the band has passed completely along the length of the shower, a stream of tobacco containing sufficient tobacco to form a tobacco filler or core has been received by the band.

The band 11 delivers the stream of tobacco over the surface of a short (considered in the direction of the moving tobacco) stationary bridge 13 and thence on to the surface of a continuous web 14 of cigarette paper.

The web 14 of cigarette paper is fed from a spool (not shown) in well known manner and is passed over a guide roller 15 and is received by a further endless band 16 hereinafter referred to as a "garniture band" which conveys the web of paper 14 together with the tobacco stream which is received on the surface of the web of paper towards and, after the tobacco stream has been compressed to form a tobacco filler or core, through a garniture, not shown, which folds the paper around the tobacco.

The garniture band 16 is folded together with the web of paper 15, but the width of the band 16 is less than the width of the paper web so as to permit the longitudinal edges of the paper web to overlap one another when the web is folded around the tobacco. When the web 14 and garniture band 16 first engage with each other they are each in a substantially flat condition, and when the tobacco stream is first delivered to the web of paper the paper web is in a substantially flat condition.

At a point which is adjacent to that at which the tobacco stream is received by the paper web 14 the paper web and the garniture band are moved into a passage 17 having converging side walls 18 and 19 and the paper web together with the garniture band 16 is folded to a U form in a manner such that the tobacco stream on the paper web is positioned in the base of the U formed by the web, see Figures 3 to 8.

The longitudinal edges of the web 14 are guarded whilst being folded into a U form so that the tobacco is retained in position on the web and does not become entangled with the longitudinal edges of the web which, as it will be understood, must be kept as free from tobacco as possible in order that the longitudinal edges may at a later stage be folded into overlapping engagement to complete the wrapping of the tobacco. The folding of the paper web 14 into U form is performed by the sides 18' and 19' of the slots 20 and 21 formed in blocks 22 and 23 respectively from which the passage is formed.

As can be seen from Figures 3 to 8 the slots 20 and 21 are of helical form so that as the garniture band 16 and the endless web 14 are moved over the surfaces 18' and 19' respectively the band and the web are gradually folded into U form, the band and web being held up against the surfaces 18' and 19' by the tension of the band 16.

The surfaces 18' and 19' respectively comprise sides of the slots 20 and 21 and by this means the longitudinal edges of the web are shrouded and the closed portions of the slots provide the guards for the longitudinal edges of the web 14.

The narrow end of the converging passage 17 communicates with a further passage 24, see Figures 2 and 9, which further passage has sub-

stantially parallel walls and is provided with elements 25 and 26, see Figure 9, which shroud and guard the longitudinal edges of the web.

The upstanding portions of the web are therefore guided by the parallel walls of the second passage and the edges of the web are guarded whilst the loaded web is being moved through the parallel passage 24.

At a position which is as near as possible to the narrow end of the converging passage 17 there is provided above the bottom of the passage and between the converging side walls 18 and 19 thereof, a movable surface which, in the drawings, is shown as a wheel 27 freely rotatable about an axis transverse to the direction of movement of the tobacco stream through the converging passage 17. The movable surface is arranged to press on the tobacco in the converging passage and to reduce the cross-sectional area of the tobacco stream to substantially the cross-sectional area which it is desired that the tobacco filler shall have. Since, however, it is not possible for the wheel 27 completely to close the space between the converging side walls 18 and 19, tongue means 28 and 29 having wedge shaped guide surfaces are disposed between the sides of the wheel 27 and the guards for the longitudinal edges of the paper web, and the wedge shaped guide surfaces of the tongue means 28 and 29 co-operate with the wheel 27 to give the tobacco stream the whole or substantially the whole of its compression independently of the action of the converging passage 17 in folding the web into U formation.

It will be seen that the compression is independent of the gradual folding of the paper web in that the folding of the paper web is gradual along the converging passage 17, whereas the tobacco is kept clear of the longitudinal edges of the paper web by means of the guards and is compressed in one stage (when, as in the construction being described only one wheel 27 is employed) at a given position in the passage, the compression being between the garniture band 16 which supports the paper web, the wheel 27 and the wedge shaped guides 28 and 29.

As will be seen from the drawings the wedge shaped guides 28 and 29 are integral with the converging side walls 18 and 19 and with the guards for the longitudinal edges of the paper web. By this means substantially the whole of the space between the sides of the rotatable wheel 27 and the converging side walls 18 and 19 is covered at the position at which the reduction of cross-sectional area of tobacco core takes place.

If desired, two or more wheels 27 with co-operating wedge shaped guides may be provided in series so that the compression would be in stages, but it will be appreciated in that case also the compression is independent of the folding of the paper web.

A stationary guide 30 is disposed above the surface of the band 11 and the paper web 14 and serves as a guide for the upper surface of the tobacco before it is engaged by the wheel 27. The guide 30, although it is shown at approximately the same distance above the band 11 and the web 14 as the lowest point on the periphery of the wheel 27, is not arranged to apply any substantial degree of compression to the tobacco before it is engaged by the wheel 27, because as will be appreciated, the tobacco

has not been gathered together due to the folding of the web 14 and the garniture band 16 and is, therefore, less dense than it is when it is engaged by the wheel 27. The guide 30 is so adjusted that it will not apply any substantial degree of compression to the web.

From Figures 4 to 8 it will be seen that the under surface of the garniture band 16 is not supported by the bottom of the converging passage 17 and by this means should there be a tendency for tobacco to become jammed this tendency will be overcome by reason of the ability of the garniture band to move towards the bottom of the converging passage, thus relieving the pressure in the passage and permitting the tobacco freely to pass therethrough.

The wheel 27 is journalled in a support 31 which is pivoted at 32 to a bracket 33 fixed to the bed of the machine. The wheel 27 is normally clamped in position as shown in Figure 1 by means of a locking device 34, the support 31 being located by a stop 35. If for any reason it is desired to obtain access to the converging passage the locking device 34 is released and the wheel 27 is swung about the pivot 32 so that the wheel is moved out of the converging passage 17.

As the compressed tobacco core is passed through the substantially parallel passage a further member comprising a rotatable wheel 36 is provided further to compress or to hold down the tobacco in the parallel passage and to guide the tobacco to the garniture in which the folding of the paper web about the tobacco folder is completed.

The periphery of the wheel 36 may, as shown in Figures 2 and 9 of the drawings, be shaped so as to conform substantially to the shape of the tobacco filler. The wheel 36 is journalled in a support 37 and the support is pivoted at 38. The wheel 36 is normally clamped in the position shown in Figure 1 by a locking device 39 and the wheel is mounted in the manner described so as to permit access to be obtained to the parallel passage 24.

After passing through the passage 24 the loaded web 14 is passed to a garniture which completes the folding of the web about the tobacco filler. The garniture comprises a first folder 40 which engages one upstanding limb of the "U" formed by the web and a second folder (not shown) which engages the other upstanding limb of the "U". Between the two folders there is provided an adhesive applying wheel 41 of any suitable known construction which applies adhesive to the

upstanding limb which is to be folded by the said second folder.

By means of the invention only a relatively small area of stationary surface engages the uncompressed tobacco stream whilst it is being compressed as compared with the area of stationary surface so engaged when a tongue as formerly used is employed.

The invention may be employed for compressing a stream of tobacco which has been formed by means of the method and/or apparatus described in United States Patent No. 2,149,924. The purpose of the method and apparatus in that patent is to make the stream of tobacco as uniform as possible, and after obtaining such a stream the tobacco is then given its compression to reduce its cross-sectional area. In order to reduce the cross-sectional area of the stream the present invention may be employed instead of the usual compression tongue referred to in United States Patent No. 2,149,924, and thus by using the present invention for compressing the tobacco one avoids as far as possible increasing any irregularities which may be present in the tobacco filler and also reduces the possibility of the formation of irregularities.

What I claim as my invention and desire to secure by Letters Patent is:

1. In a cigarette making machine, folding elements to fold a web of wrapping material around a stream of tobacco, means to feed a stream of tobacco and a web of wrapping material lengthwise to said elements, stationary tongue means comprising curved tobacco engaging surfaces for pressing the tobacco stream, said surfaces converging towards each other, a converging passage coating with said feeding means to fold the web to a "U" formation with the tobacco stream positioned in the base of the "U", guard means extending from the sides of the tongue means to the converging passage to keep tobacco away from the longitudinal edges of the web in the converging passage, a movable presser element having a movable tobacco engaging surface extending through the tongue means, the movable surface and the tongue means cooperating to press the tobacco stream.

2. A cigarette making machine as claimed in claim 1, wherein the compression tongue is formed in two separate longitudinal parts, being spaced apart to provide a passage having opposed parallel walls, and wherein the movable compression element extends between the parallel walls to engage the tobacco.

FÉLIX FRÉDÉRIC RUAU. 55
